UNITED STATES PATENT OFFICE.

LORENZ KONRAD BRAREN, OF MUNICH, GERMANY, ASSIGNOR TO THE FIRM FRIED-RICH DECKEL, FABRIK FÜR PRAZISIONSMECHANIK UND MASCHINENBAU, OF MUNICH, GERMANY.

SCREW MAKING AND TURNING MACHINE.

Application filed November 28, 1922, Serial No. 603,871, and in Germany December 17, 1921.

This invention relates to improvements in screw making and turning machines, and particularly to that class of machines known as automatic screw machines, which machines are characterized by producing automatically screws, studs, pins, rollers, nuts, formed parts and the like from a bar of material or a wire completing as a rule one part for each revolution of the main cam shaft. The tool holders I prefer to use are pivoted and swing towards the bar of material under the action of the various cams, the invention of course may be applied just as well to machines using tool holders in the form of slides.

An important object of this invention is the arrangement of cutting means with the feeding mechanism in such a way that these cutting means move forward together with the material and that during the feeding period they can be operating radially towards the center of the material as for instance cut off and form tools, while other tools not connected with the feeding mechanism may swing into the material and perform turning operations. A support for the bar of material not partaking of the axial movements of the feeding mechanism has been provided close to the cutting tools.

I also provide means for regulating the movement of the feeding mechanism in such a way that it is not only possible to produce with one set of cams, screws, studs, etc., with different total length but these parts may be made also with heads or turned portions of varying length.

Another object of this invention is the provision of means for changing the amount of movement of the swinging tool carriers without changing cams.

Another important part of this invention is a thread cutting mechanism constructed adjustable to advance the die or tap according to the lead and means for reversing instantaneously the relative movement between main spindle and threading spindle and for pulling the threading tool back at the same moment.

The above and various other improvements will be hereinafter fully described and claimed.

Some of the features shown and described, but not claimed in this application are shown, described and claimed in my copend-

ing applications filed June 4, 1924, and Oct. 55 6, 1924, and serially numbered 717,713, 717,714 and 741,913 respectively.

In order that this my invention may be more readily understood reference is made to the accompanying sheets of drawings 60 which show how this invention may be carried into practical effect.

Fig. 1 is an end elevation of the machine, Fig. 2 is a front elevation of the machine proper without the stand and motor drive. 65 Fig. 3 is a top plan view of the machine, the turning tool holder being broken off. Fig. 4 is a front elevation of the machine in section on the main spindle line. Fig. 5 is a section through a spring collet. Fig. 6 is 70 a section through the right hand end of the machine on the auxiliary cam shaft line looking in the same direction as in Figure 4. Fig. 7 is a top sectional view of the feed actuating slide. Fig. 8 is a side view of 75 the same slide partly in section. Fig. 9 is an elevation of the gear case looking from the right hand side, the cover and the drive clutch mechanism having been removed. Fig. 10 is a horizontal section through the 80 gear case with the feed actuating slide taken off. Fig. 11 is an end elevation of the machine from the right hand side partly in section the gear case having been removed. Fig. 12 shows the machine looking from the 85 left hand side with the threading mechanism removed. Fig. 13 is an end elevation of the threading mechanism looking from the left hand side. Fig. 14 is a section through the oil pump and the lubricating arrangement. 90 Fig. 15 is a section through the oil pump at right angles to Figure 14. Fig. 16 is a rear elevation of part of the machine, with the drive clutch and the threading mechanism taken off. Fig. 17 is a perspective view of 95 the drive clutch engaging lever. Fig. 18 is a view of the clutch on the auxiliary cam shaft. Fig. 19 shows the provision for lubricating the main spindle and Fig. 20 the bearing of the main spindle. Fig. 21 100 shows the spring barrel for the threading mechanism. Figs. 22 and 23 give two views of the levers actuating the swinging arm of the slotting mechanism. Figs. 24 to 40 show the parts produced in the machine. Fig. 41 105 is a top view of the adjustable guides for the threading mechanism.

Referring to the drawings in which like

characters of reference indicate corresponding parts wherever occurring, the driving pulley 12 of the machine proper receives its motion through a belt 8 from the motor pulley 11. (Fig. 1.) The motor 1 is fastened to a base plate 2, swinging on a pin 3 which is held in a bracket 4 screwed to the stand 5 of the machine. A spring 6 carries part of the weight of the motor base with motor and can be adjusted through screw 7, regulating thereby the tension of belt 8. The oil pump pulley 10 is located in such a way that it is actuated by belt 8, the idler 9 giving a greater arc of contact.

15 Pulley 12 with webs for guiding the belt sideways is formed on the inside to mate with a cone clutch 13, which is fastened rigidly through a key and a screw 14 to the drive shaft 15. (See Fig. 4.) A hand-wheel 16 for turning the machine by hand is fastened to the cone clutch 13. The hub of pulley 12 is bored to turn and slide freely on the outside of bushing 17 which latter is pressed into a hub of the cover 18 of the gear box 19. Spring 20 tends to hold the coupling out of engagement, a thrust plate 21 being interposed between the spring 20 and the cone clutch 13.

20 A handle 22 for starting the machine is pivoted on a pin 27 which is fastened in a lug 23 of the gear case cover 18. (Figs. 2, 3 and 10.) Lever 24 (see Fig. 17), also pivoting on pin 27, is forked to reach out over the hub of pulley 12 and carries two 25 sliding shoes 26 fitting in a groove 25 provided in the hub. On the opposite side the lever 24 extends with plate like portions 24^a over and under the handle 22, a part 28 connecting these two plates together. Pin 30 fastened in handle 22 passes through a slot in the top plate of the lever 24 and limits the movement of the handle 22 and the lever 24 in relation to each other, a spring 29 tending to force them apart. A nose 31^a is formed 35 on the end of the lever 31 which is pivoted to a lug of the gear case 19 and can hook under a plate 32 fastened to the handle 22. A spring 33 pulls the lever 31 up against the plate 32.

40 In order to engage the driving pulley 12 with the cone clutch 13 the handle 22 is pushed towards the left until the nose 31^a on the lever 31 under the action of the spring 33 can snap upwards and hook in back of the end of the plate 32 preventing thus the return of the handle 22. The lever 24 moves together with handle 22 until pulley 12 has been brought into contact with the clutch member 13. A further movement of the 45 handle 22 compresses the spring 29 and this spring pressure furnishes the necessary coupling pressure. In order to keep the coefficient of friction in the cone clutch constant a lubricant retainer 13^a has been fastened to pulley 12. To stop the machine it is only

necessary to push nose 31^a downward because the spring 29 returns pulley 13, lever 24 and handle 22 to nonrunning position.

To stop the machine automatically after a rod of material has been used up, a lever 70 35 is pivoted inside of the gear case and provided with a hole 36 for the passage of the material. (Fig. 9.) As soon as the end of the rod has passed through this hole, the spring 37 pulls the lever 35 down and an arm 75 35^a of this lever, protruding through a slot in the gear case 19 towards the outside, lifts by means of a chain 34 the arm 38 of the lever 31 thereby disengaging the plate 32 and freeing the driving clutch.

80 The drive shaft 15 transmits the movement from the clutch member 13 by means of a fluted portion to two gears 39 and 40 and finds a bearing in the bushing 17 on the one end and in a bore of gear 39 at the other end, the hub of this gear being journaled in and extending through a hub 43 of the gear case 19. (Fig. 4.) A washer 45 and a collar 44 fastened to the hub of gear 39 fix the axial position of the latter, while a collar 41 pinned to the shaft 15 and a thrust washer 42 hold the gear 40 and the shaft 15 against axial movement. By this arrangement shaft 15 and the complete clutch mechanism can be removed together with the gear case cover 18, facilitating thus the changing of the gears.

85 The intermediary shaft 47, which also drives the slitting saw mechanism, receives its motion through a gear 46 in mesh with gear 39. Main shaft 50 extending through the length of the machine and driving the material and the threading spindle is connected to the intermediary shaft 47 through 90 change gears 48 and 49. Another pair of change gears 51 and 52 drives a shaft 53 which is journaled in bushings located in the gear case 19 and the cover 18. (See also 95 Figs. 6 and 9.) A miter gear 54 fastened to the shaft 53 turns the worm shaft 57 through 100 the miter gear 55 which is an integral portion of this shaft. Worm shaft 57 is journaled in a lug 56 and a bearing 56^a of the gear case 19 the thrust being taken up by a ball bearing 58 through a screw fastened in shaft 57. A plate 59 closes the opening in the hub 56^a of the gear case 19. A worm gear 60 is fastened on cam shaft 61 and stands in engagement with worm 57.

105 By this arrangement the speed of the intermediary shaft 47 driving the slitting saw remains constant while the speed of the main shaft 50 and therewith the speed of the material and threading spindle is varied through the change gears 48 and 49 while the speed of the cam shaft 61 in relation to the speed of the main shaft is changed through the gears 51 and 52.

110 In order to perform very quickly any noncutting operations as for instance re-

moving the cut off tool out of the path of the material, pulling back the feeding mechanism for operating on the next part and advancing that portion of the part, which is not turned, an auxiliary cam shaft consisting of two parts 65 and 65^a is provided. (Figs. 6, 9, 10 and 18.) These parts are joined together by a simple jaw clutch 79 to facilitate the removal of either end. To accomplish the desired object, that is: to rotate the cams mounted on the auxiliary cam shaft slowly during the cutting operations and very fast during the nonproductive period and yet complete each revolution synchronously with the main cam shaft, two gears 63 and 69 are provided, of which gear 63 is driven by the slowly rotating cam shaft 61 through gear 62 while gear 69 is rotated by the fast running drive shaft 15 through gear 40, and the auxiliary cam shaft 65 is coupled alternately with these two gears 63 and 69. The clutch 67, disposed between the gears 63 and 69, is mounted slidingly on but fixed rotatably to shaft 65 by means of a pin 72 which is driven into shaft 65 and located in slots cut into the clutch. Two notches spaced at 180° are cut into one face of the clutch 67 and two corresponding noses 66 integral with gear 63 fit therein, while clutch teeth 68 have been cut into the opposite face and mate with teeth cut into the hub of the gear 69. Gear 63 is journaled with a hub in a bearing of the gear case 19, a collar 64 holding it against axial movement. Similarly gear 69 finds a bearing in the gear case cover 18 with a collar 70 preventing axial play. Thrust ball bearings are interposed between the gear 69 and the cover 18 and the gear 69 and a collar 73 in order to take up the spring pressure exerted on the collar 73 by the nose 77 fastened to a lever 74. This lever 74 is pivoted to a hub in the gear case 19 and stands under the influence of a spring 75. Two fork like ends of lever 74 reach over and under clutch 67 and carry two rollers 76, which come into contact with a rim on clutch 67, when the nose 77, which is fastened to the lower arm of the fork, drops into a recess 78 cut into the face of the collar 73, and throw, actuated by spring 75, the clutch 67 into mesh with the gear 69. The collar 73 is fastened by the pin 72 to the auxiliary cam shaft 65 and both rotate in unison with the clutch 67. Rotating in direction of the arrow after the nose 77 has dropped into the recess 78, a gradual slope on the backside of this recess pushes the nose 77 and the lever 74 with the rollers 76 back to the original position. Spring 71 which is disposed around shaft 65 tends now to throw clutch 67 out of mesh with gear 69 and back into engagement with gear 63 but cannot effect this movement until the notches in the clutch coincide with the two noses 66 on gear 63, which occurs

after a relative movement of 180° between the clutch 67 and the gear 63. The spring 75 of course must be considerably stiffer than the spring 71 in order to effect the movements as described.

In order that the auxiliary cam shaft 65 may complete each revolution in the same time as the main cam shaft 61 gear 63, in case two noses 66 having been provided, must rotate half as fast as gear 62 or have double the number of teeth. In this case the auxiliary cam shaft 65 rotates approximately half a revolution slow, being coupled with the main cam shaft 61 and half a revolution fast in engagement with the drive shaft 15. Actually it moves somewhat more than 180° fast, because the slowly running gear 63 progresses also a certain distance during the fast movement of the clutch 67. Supposing a different number of noses 66 have been chosen, the ratio, between the gears 62 and 63 and between the fast and the slow movement of the shaft 65 must change correspondingly.

The cam 82 for controlling the feed movements and the cam 83 for the cut off tool are located on the auxiliary cam shaft 65, a fluted portion of the shaft 65^a fitting in cam body 81. A flat spring 80 which may be swung out of the way but is held in position by a conical pin 80^a entering the center of shaft 65^a prevents any endwise movement of this shaft. In this way the cam body 81 can be readily removed. Two cam plates 82 and 82^a are formed integral with the cam body 81. The cut off cam 83 is secured rigidly to the cam body 81.

A slide 84, controlling the feeding mechanism is moved upwards by the cam 82 and downwards by the cam 28^a, the rollers 85 and 86 transmitting the movement. To reduce friction balls 89 held in retaining plates 90 are arranged on both sides in V grooves of the slide 84 and in similar V grooves of the blocks 87 and 88 which are fastened to suitable faces of extending arms of the gear case casting 19. The movement of the ball retaining plates 90 is limited at the bottom by stop plates 94 and on the top by the cover 91. The latter is pivoted on pin 92 to lugs of the gear case 19 and is held down by a thumb screw 93 which is fitted so as to enable the operator to swing the cover back after loosening the screw a quarter of a turn, a slot in the cover plate 91 letting the flat head of the screw 93 pass through. (Fig. 11.) For guiding the feed mechanism actuating arm 111, there is provided a plate 91^a on the cover 91. The movement is transmitted from the slide 84 to the arm 111 by a roller 98 turning on a stud 108 which is fastened to an extending part 110 of the arm 111, a washer 109 being interposed in back of the roller.

The movement of the slide 84 is trans-

ferred to the roller 98 through two adjustable guide blocks 96 and 97 which are arranged in a recess 95 of the slide 84. (Figs. 6, 7, 8 and 16.) The guide blocks 96 and 5 97 can be adjusted individually to different angles but are connected together by a pivot stud 100 on which both turn.

A stud pin 99 is pushed into a hole of the 10 slide 84 the guide 96 with an elongated slot sliding on a shoulder of this pin. In a similar way guide 97 is sliding with an elongated slot over the shoulder of the stud 101. Both 15 studs 100 and 101 have a square body fitting into slots 102 and 103 of the slide 84 and are adjusted sideways by means of screws 104 and 105. These screws are secured against end movement by two locknuts 106. The heads of the adjusting screws 104 and 20 105 are graduated like a micrometer barrel a reading mark being provided on the rear face of the slide 84. (See Fig. 16.) The washers 107 are milled off sideways to fit 25 into the slots 102 and 103 and both carry reading marks which together with a scale 108 on the rear face of the slide 84 facilitate the adjustment of the guide blocks 96 and 97. After the setting has been completed the 30 guides are pulled down tight to the slide 84 by the nuts on the studs 100 and 101. The curves of the cams 82 and 82^a are formed so that during the slow movement of the auxiliary cam shaft the roller 98 is pushed 35 sideways by the lower guide block 97 moving upwards, while during the fast movement of the auxiliary cam shaft, the roller 98 stands under the influence of both guide blocks moving downwards and of the upper one 96 moving upwards. Therefore, in setting 40 the guide blocks, the upper screw 104 has to be adjusted until the height of the head of the part to be manufactured plus the thickness of the cut off tool are indicated on the upper scale, while the total length of 45 the part plus the thickness of the cut off tool determines the adjustment of the lower screw 105.

The feed mechanism actuating arm 111 50 which is rotatably mounted on the bushing 112 transmits the axial movement impressed upon it by the slide 84 to the bushing 114 by means of a gooseneck arm 113 extending around bushing 114 and fitting with two 55 keylike projections into a groove 115 of said bushing. The latter slides in a bushing 117 pressed into a hub of gear case 19. The bushing 114 is prevented from turning by a key 118. A tubular part 119 fits rotatably 60 into the bore of the bushing 114 and is held axially by a washer 120 and two lock nuts 121. Longitudinal holes with felt inserts in the walls of the bushing 114 insure a good lubrication. Another tubular member 122 is 65 screwed over the enlarged end of the part 119 and is slidingly located in a bore of the main spindle 123, a key preventing rotation.

Part 119 serves as a retainer for three steel balls 124 which fit easily between the faces of the parts 119 and 122 and rest in grooves cut with an incline onto the three jaws of a spring collet 125 which is slidingly located 70 in a bore of the part 122 and pressed by a spring 126 towards the rear, making thus the balls roll up on the inclined grooves, close the jaws of the collet, and grip the rod of material 127. The parts just described are 75 the complete feeding mechanism.

Working together with the feeding mechanism there is provided a material holding 80 spring collet 128, with three balls 129 working in similar inclined grooves of the collet 85 jaws, a spring 130 for closing the jaws and a ball retainer 132. Part 132 is screwed onto the nose of the main spindle 123. A cap 134 serves for holding the balls in place. A nut 131, screwed to the end of the spring 85 collet 128 helps to guide the collet in the bore of the main spindle 123, while the bushing 133 serves the same purpose for the retainer 132 into which it is pressed.

The bar of material 127 is guided loosely 90 on its entrance into the machine in the bushing 135. Guide bushings 136 and 137 are pushed into the ends of the spring collets 125 and 128 and serve especially for steady- 95 ing material of small diameter. All bushings and collets through which the rod of material is passing are countersunk on the entering side.

The two spring collets are arranged in 100 such a manner that the material may pass 100 through them readily in the feeding direction because end pressure in this direction is transmitted by friction to the collet, releasing the balls and allowing the material to slide through easily. Any end pressure in 105 the opposite direction however forces the balls tighter onto the jaws increasing the grip on the material in ratio with the end pressure, with suitable inclination of the 110 grooves locking the rod entirely.

The whole feeding process therefore requires only a movement back and forth of the spring collet 125, which is accomplished by the guide pieces 96 and 97 as previously described. The material is always held securely by one of the collets thus insuring an 115 exact and uniform feed.

For a different size of material the spring 120 collets of course must be exchanged. The collet 128 may be replaced readily by unscrewing the ball retainer 132 from the main spindle 123 and removing the collar 131 by the screw driver slot in the rear. To exchange the spring collet 125, the cover 91 is swung 125 out of the way giving the key 116 of the arm 111 free.

The keylike projections on arm 111, fitting into the groove 115, can now be swung out of the way, the bushing 114 may be pushed towards the right, and the threaded connec-

tion between the parts 119 and 122 parted. Collet 125 can now be exchanged. To enable the operator to push the bushing 114 back with a wire a small hole 138 has been drilled 5 through the bushing 135.

To prevent any end movement of the main spindle 123, there have been provided two bearings 141 and 143 with a tapering bore of which the former is pressed into, while 10 the second is held adjustably by two screws 144 in hubs of the main frame 142. On the central portion of the main spindle teeth 139 have been cut, which stand in engagement with a gear 140. This gear is driven by a 15 fluted portion of the main shaft 50 and supported by two bearings 147 and 148 with similar tapering bores as the bearings 141 and 143 have. Bearing 147 with a tubular extension 149 is pressed into a hub of the 20 main frame 142, while the bearing 148 also with a tubular extension 152 is adjustably located by a screw fastened in a bushing 150, which latter is held in place by a set screw 151.

25 The lubricant taken up by the gears 139 and 140 is thrown off against the faces of the bearings and caught by oil grooves 145, which are milled with a wide opening on the side towards the gears, and led to oil holes 146 connecting with spiral oil grooves 153 on the tapered ends of the main spindle 123. (See also Figs. 19 and 20.) The spirals on both ends are cut in opposite direction in order to pump the lubricant back to the oil 30 space at the center. To prevent the lubricant, which is thrown in large volume onto the material and the cutting tools, from being thrown off by the fast rotating spindle an oil guard 154 is pushed into a corresponding recess in the bearing 141, a T slot being 35 cut into the oil guard to effect a slightly springing action.

Moving endwise together with the feeding mechanism there is arranged a cut off 40 tool carrier 155 and an arm 156, which is clamped over an end of this carrier by two screws 157, whereby a certain adjustment of the tool carrier 155 is made possible. (See Figs. 2, 3, 4 and 11.) The arm 156 is cut out 45 to fit over the bushing 112 on both sides of the feed actuating arm 111 with two ball thrust bearings 158 interposed. Screws 159 clamp the split sides tight to the bushing 112. A series of balls 160 in a ball retainer 50 161 are arranged between the bushing 112 and the tubular extension 152, reducing thus the friction and also the thickness of the oil film, whereby the precision of the movements 55 is enhanced considerably. In a similar way another series of balls 162, for the bushing 164 to slide and turn on, is placed in a retainer 163 around the tubular extension 149. The bushing 164 is pressed into a hub of the 60 cut off tool carrier 155. Rotatably mounted 65 on the same bushing is a form tool carrier

165, lock nuts 166 and washers preventing undue end movement. To prevent chips from entering into the space around the balls cover plates 167 and 168 are fastened to both ends of the bushing 164.

The radial movement of the cut off tool carrier is controlled by the cam 83, an adjustable nose 169 with a wedge shaped end sliding on the circumference. (Fig. 11.) This nose 169 is located in an arm 170 of a 70 rocker frame 171 which turns on two pintle screws 172 and 173, lugs being provided for them on the main frame 142. A roller 174, which is mounted on a bushing 175, can be adjusted towards and away from the fulcrum of the rocker frame 171 by means of a threaded stud 176 a nut 177 locking after adjustment. An extension 178 of the arm 156 carries a hardened plate 179 for contacting with the roller 174. A spring 180 is located in a barrel 181 and presses a plunger 182 against the arm 178 causing thereby the rocker frame 171 and the cut off tool carrier 155 to follow the curvature of the cam 83. To reduce friction between the spring plunger 182 and the arm 178, when moving the cut off tool carrier endways, a ball 183 resting on three smaller balls is inserted in the plunger 182, a plate 184 preventing the balls from dropping out of the 85 recess.

With the arrangement of operations as usually followed in this machine, the cut off tool is operating continuously, excepting of course the small amount of time consumed during the fast movement of the auxiliary cam shaft, when the tool is pulled back and shifted together with the feeding mechanism. With the adjustable roller 174 mounted on a 90 rocker frame, which is interposed between the cam and the tool carrier, it is therefore possible to use one and the same cam for all different kinds of pieces by varying only the movement of the cut off tool according to the diameter of the rod of material.

The circular cut off tool 185—of course a flat tool might be used as well with a correspondingly different holder—is fastened to a tool holder 186. (Figs. 3 and 12.) This holder is located on a stud 187 which passes through a lug of the slide 189 and can be adjusted in and out by two check nuts 188. Adjustment of the tool up and down is secured by the two screws 190 and 191 rocking the holder slightly on the pivot stud 187. The slide 189 can be adjusted on the carrier 155 towards and away from the center by means of two screws 192 and 193. While the former is threaded in a plate 184 and rests with the point against the carrier 155, the latter 193 is threaded into the carrier 155 pulling the slide 189 towards the center.

The description of the cut off tool holder applies also to the other tool holders. (Figs. 2, 3, 12 and 16.) The form tool holder 194

is mounted on a carrier 165 and a turning tool holder 195 on a carrier 196, which latter is pivoted on a stud 197 pressed into the main frame 142, two check nuts 198 taking up any axial play. The turning tool in this way is axially fixed, while the other two tool holders move together with the feeding mechanism. A nose 199 is fastened to the carrier 196 and is held by a spring 200 against a cam 201 while the form tool carrier 165 carries a blade 202 sliding on a cam 203.

In the construction shown the parts are threaded by the differential method, that is 15 the tap or die is run with a different speed as the constant speed of the main spindle. With the direction of rotation of the main spindle as chosen the threading spindle must run faster than the main spindle for 20 cutting a right hand thread and slower or stop for running the die or tap off the work. For left hand threading on the other hand the threading spindle must run slower for cutting and faster for running off.

25 The whole thread mechanism is mounted on a bracket 208 which is fastened by screws to a seat of the main frame 142 and can be removed as a unit. (Figs. 2, 3, 4 and 13.) The tubular part 149 is supported in a hub 30 209 of the bracket 208 and extends through it to furnish a pivot for a bushing 205 of the spindle carrier. An arm 210 is screwed to the bracket 208 and has a bore in line with the hub 209, this bore providing a bearing 35 for a bushing 211 which is pressed into the spindle carrier. The spindle carrier consists of two parts 206 and 207, which are bolted together and mounted rotatably on the axis of the main shaft 50 and held sideways by 40 the hub 209 and the arm 210. A driving gear 204 is located between the halves of the spindle carrier 206 and 207 and turns with a hub in the bushing 205. Thus it is possible to remove the main shaft 50, which drives 45 the gear 204 by a fluted portion, without disturbing the location of the gear. Spindle gear 212 finds a bearing in the bushing 213, thrust washers 214 being provided. On the 50 opposite side the gear 212 is bored out to mate with a cone clutch 215, which latter extends as a tubular part through the bearing 216 of the spindle carrier half 207. A collar 217 fastened to the end of the tubular cone clutch 215 transmits any rotative movement 55 to the threading spindle 218 two key like projections fitting slidably in grooves of the spindle. The threading spindle 218 slides in the end of the tubular extension of the cone clutch 215 and slides and rotates in the bushing 213. For cutting an external thread the die holder 219, with the die 220 held to it by a threaded cap 221, is provided with a threaded part, over which the locking nut 222 is screwed pressing in this way the slotted prongs of the holder 219 tight to the

spindle 218, permitting an easy way of adjustment. For gripping a tap, a drill or similar tool a chuck resembling the die holder is employed. A spring 223, arranged in the space between the spindle 218 and the cone clutch 215, tends to hold the latter in engagement with the gear 212. The threading spindle rotates during the period of engagement faster than the main spindle 123 when, as in the present case, the gears 204 75 and 212 have been chosen for cutting a right hand thread.

Two rollers 224, which can come into contact with the collar 217, are rotatably fastened on an arm 225 which is pivoted by a pin 226 to a lug of the spindle carrier half 207. Another roller 227 is also pivoted to the arm 225 and is located in the path of a lever 228, which swings on a stud 229 screwed to the thread mechanism bracket 208. A spring 230 pushes the lever 228 against the roller 227 bringing thereby the rollers 224 to bear against the face of the collar 217 and pulling the cone clutch 215 out of engagement with the gear 212 overcoming the resistance of the spring 223. A plate 232, shaped like a quarter of a ring with a gradual rise on one end and cut off squarely at the other end 232a, is fastened to the side of the cam 231 and pushes in the corresponding position the nose 233, which is fastened to the lever 228, against the pressure of the spring 230 back, releasing thereby the arm 225 and allowing the spring 223 to engage the cone clutch with the gear 212. The point 232a is adjusted so that the nose 233 drops off with the spindle furthest advanced towards the material, thus timing exactly the moment of the reversal of the relative motion between the threading spindle and the main shaft with the moment of the reversal of the axial movement of the threading spindle.

A slide 234 with a nose 235 fastened to it is held by the pull of a spring 236 against the cam 231. Two adjustable guide pieces 237 and 238 are fastened to the slide with one end by means of a screw 239, sliding with a head in a T slot which is cut into the body of the slide at right angles to the movement 115 (see also Fig. 41). A scale 240 and an adjusting screw 241 with graduations on the head provide easy means for adjustment; a nut 242 clamps the guide pieces rigidly to the slide. The other end of the pieces 237 120 and 238 are guided with slots over shoulder studs 243 and 244 pushed into the slide 234. The arrangement and adjustment of these guide pieces is very similar to the construction of the guides 96 and 97 for actuating 125 the feed mechanism.

To transmit the movement from the guides 237 and 238 to the threading spindle 218, there is arranged a lever 246 with a roller 245 at one end. The lever 246 is fastened 130

- on a pin 247 which turns in lugs of the arm 248. The arm 248 is pinned to a rod 249 and is held by means of a spring 250 against the face of the tubular part 251, which is 5 pressed into the bushing 211, a screw 252 holding the rod 249 and the lever 246 against turning, a slot in the rod 249 allowing a certain movement endwise. This elastic connection has been provided in order to prevent 10 any damage in case the threading spindle meets undue resistance. To reduce friction a ball 253 resting on three small balls has been inserted into the end of the lever 246 resting against the spindle 218.
- 15 The cam 231 for advancing the spindle rotates in the direction indicated by the arrow on Fig. 13. It has a portion with a steep rise and then up to the point 231^a a considerable part with constant rise designed 20 to move the slide 234 equal distances for equal angular movements of the cam. As the relation of rotation of the camshaft 61 and of the main spindle 123 and also the relation of the main spindle and the threading 25 spindle 218 is fixed by gears, it is possible to adjust the guide 237 to an angle so as to advance the spindle 218 the correct amount for the lead of the part being threaded. The drop of the cam 231 from 30 the point 231^a on is also designed with a constant decrease which makes the threading spindle move off at the proper speed. The guide 238 is adjusted to a greater angle in order to move the threading spindle 35 out of the way when not in operation.
- The spindle carrier 206 and 207 is mounted rotatably on the axis of the main shaft 50 as has been described previously. A stop screw 254 passing through the head of one 40 of the connecting bolts of the carrier halves permits the exact alignment of the threading spindle with the main spindle. A spring 255 is located in the spring barrel 256, which is pivoted on two pintle screws 257, and 45 pushes by means of a spring plunger 258, which is pivoted to a lug of the carrier 207, the stop screw 254 onto its seat. (See also Fig. 21.) In order to swing the carrier out 50 of the way, which is of advantage in changing collets and for removing the short ends of material left of each bar, the operator only pushes against the top of the carrier 206 and 207 compressing the spring 255 and swinging the spring barrel 256 until 55 the line of action of the spring passes the turning axis and the carrier is brought against the bracket 208. The roller 227 rolls during this movement on a correspondingly formed surface of the lever 228, while the 60 lever 246 moves away from the guide piece 238 but is brought up against it by the return of the carrier to the normal position.
- The main cam shaft consists of two parts 61 and 61^a and is driven by the worm gear 60 as shown previously. (Figs. 3, 10 and
- 16.) A coupling sleeve 259 is pinned to the end of the part 61, while the part 61^a is connected to it by screws 260 which clamp the split sleeve onto the shaft. The cam 201 fits over a turned down part of the sleeve 259, 70 while a pin 261 driven through a shoulder on the sleeve and passing into a hole of the cam establishes a positive relation. A nut 262 holds the cam against the shoulder of the sleeve. Another cam carrying sleeve 263 75 is pinned to the shaft 61^a and the cam 203 is held by a nut 264 against a shoulder of this sleeve, a pin 265 establishing the relation between cam and cam shaft. A pin 266 driven into the shoulder from the opposite 80 side fits into a slot of the sleeve 267, which is mounted rotatably over the hub of a cam 268. Three screws 269, 120° apart, passing through slots of the sleeve 267 are screwed into the cam 268 allowing a considerable 85 degree of adjustment of the cam 268 in relation to the cam 203. A cam 270 is fastened to the cam 268. A thrust washer 271 is interposed between the cam 268 and a bearing 90 of the thread mechanism bracket 208. The thread mechanism actuating cam 231 is pulled up against a shoulder of the cam shaft 61^a by a nut 272, a key establishing the proper relation.
- Thus the cams on the auxiliary cam shaft 95 stand in unchangeable relation to the cam 201, which actuates the turning tool, while the form tool cam 203 and the thread mechanism cam 231 are tied together but the latter two can be adjusted in relation to the 100 former cams by loosening the clamping screws 260 and by turning the cam shaft 61^a in relation to 61 indicating lines being provided on the parts 259 and 263.
- A slotting saw 273 is mounted between a 105 collar 275 and a nut 274 on a shaft 276 which latter is supported in bearings of a housing 277. (Figs. 2, 3, 4, 12, 22 and 23.)
- A spiral gear 278 is fastened to the other end of the shaft 276 and is driven by the 110 gear 279 which is cut onto the end of the intermediary shaft 47. The housing 277 fits slidingly over a bushing 280, which is fastened in bores of the main frame 142 and the gear case 19, and is held by a screw 281 115 passing through an elongated hole of a lug 277^a to a seat on the main frame 142. By means of this slot it is possible to adjust the housing with shaft and slotting saw back and forth in correspondence with the length 120 of the part to be slotted.
- A swinging arm 282 carries a bushing 283 fitting over the finished part and takes the latter from the main spindle after it has been cut off to the slotting saw. The arm 282 is held adjustably by a screw 285 clamping the split hub to a sleeve 284, which latter slides and turns on a rod 286 pinned to the thread 125 mechanism bracket 208. A lever 288 is pivoted on a stud to a boss of the main frame 130

and carries at one end two rollers 287 which fit into a groove cut into the sleeve 284, while a roller 289 at the other end is held in contact with the face of the cam 268 by a spring 297 mounted on the rod 286 and pressing against the sleeve 284. In this way the screw is not fed positively against the slotting saw, but by the elastic pressure of a spring. The swinging movement of the arm 282 is controlled by the cam 270 through the lever 291, which is pivoted to a boss of the thread mechanism bracket 208 and carries at one end a roller 292 in contact with the cam, while the roller 293 at the other end rests on a square sleeve 290 pivoted by a stud to a lug of the arm 282. A lever 295 pivoted to the lever 291 holds by means of a roller 294 and an adjustable spring 296 the sleeve 290 and the arm 282 against the roller 293, a spring 298 holding the roller 292 against the cam 270. Thus the movement of the arm 282 in both directions is controlled by springs, and adjustable stops 311 and 312 are provided, the former in the arm 282 and the latter in the housing 277. A pin 299 for removing the slotted pieces out of the bushing 283 is fastened in a cover 300 which is attached to the housing 277. The completed parts drop into a container 301 fastened to a lug of the slotting saw housing.

A reservoir for lubricant has been provided in the upper part of the stand 5 by a wall 302, a cross wall 309 dividing the space into two compartments, of which the larger one serves for allowing impurities and chips to settle, while the lubricant is pumped out of the second and thrown onto the cutting tools returning through a cover 313 with a fine-meshed screen to the larger compartment. (Figs. 14 and 15.) The opening in the cover wall is large enough to permit the removal of any sediment. Two gears 304 and 307 are located in a housing 305, which is screwed to a seat on the stand 5, a plate 306 being interposed. The gear 304 is fastened to one end of a shaft 303 while the pulley 10 is secured to the other end of this shaft, this pulley being rotated by the drive belt 8 as previously shown. The suction space between and underneath the two gears is connected by a bore 310 in the intermediary plate 306 to the suction pipe 308, while the compression space is connected on the one hand by an oblique hole 315 to the pressure line 316 which leads through a hole in the cover wall 314 to the cutting tools, a cock 317 being interposed for regulating the amount of flow of the lubricant or shutting it off entirely. On the other hand the compression space is connected to a relief valve screwed into the plate 306 and consisting of a tubular part 318, a spring 319, a ball 320 and a cap 321 with a hole for holding the spring in place. As soon as the pressure rises above a certain point determined by

the tension of the spring 319 the ball 320 is lifted from its seat and the fluid escapes through the hole in the cap 321.

The various mechanisms are grouped in units which can be removed readily as a whole from the machine. The machine proper is screwed to pads 322 and 323 cast on the cover wall 314 and can be taken off the seat bodily after loosening these connecting screws.

The gear case 19 is fastened to the main frame 142 by two screws 324 on the right hand end and by two screws 325 on the rear (Figs. 3, 4 and 16). To remove the gear case together with the feed actuating slide 80 it is necessary to take off the drive belt 8, open the cover 91 and swing the arm 111 towards the front, to loosen the screws 260 61 and 61^a and remove the screws 324 and 325. Now the gear case can be taken off, the intermediary shaft 47 and the main shaft 50 coming off together with the gear case.

The thread mechanism on the other end 90 is mounted on the bracket 208 and can be pulled off complete after taking out the fastening screws 326 and taking off the nut 272 and the cam 231 on the end of the cam shaft 61^a. After removing the thread mechanism 95 the slotting arrangement may be taken off by removing the screw 281 and sliding the complete housing off the intermediary shaft 47 or rather off the tube 280.

After having explained in detail the construction of the various mechanisms of this machine and their functions, I will show how by means of these improvements and their combination a part, which is suitable for the range of a machine of this kind, can 105 be manufactured at an exceedingly fast rate, in fact several times as fast as was heretofore possible, and I am also going to explain how one set of cams is sufficient for all ordinary parts.

To produce a screw, for instance as shown in the Figures 24 to 35, it is necessary to perform a number of operations namely turn the body, cut a thread onto it, cut the part off, cut the screw slot into the head, and advance the material for the next part. The time it takes to produce a piece is the sum of the times necessary for the single operations. Any operation of course, which is performed together with other operations, is not to be 115 counted. Multiple spindle machines have been constructed and are used widely where one piece is completed during the time necessary for the longest single operation. A number of spindles and rods of material are 120 arranged in the machine with a similar number of working stations and the rods pass from one station to the next until the part is completed after having passed all stations.

With the present construction it is also 130

possible to complete one part during the time taken for the longest operation. For short parts, that is for parts with a length of the turned body of not more than two and a half times the diameter, and only a very limited number of parts do not fall under this category, the cut off operation is the longest operation. The other operations are all performed during the time taken for completing the cut off as is shown in the diagrams Figs. 24 to 35. The arrows on the diagrams indicate the direction of movement of the material, threading die, cut off and forming tool.

Fig. 24 shows the position of the various instrumentalities during the fast movement of the auxiliary cam shaft when the feed actuating slide 84 has just passed the lowest position and the feed mechanism with the cut off tool carrier is beginning to move forward. At this moment the turning tool T stands stationary, away from the path of the material, the threading die D is moving towards the material and rotates at a faster speed than the rod of material M, on which the body of the screw has been turned and which is moving outwards together with the cut off tool C under the influence of the fast rotating cam 82. The slotting arm S is carrying the completed screw to the slotting saw.

Fig. 25 shows the position shortly after the slow movement of the auxiliary cam shaft has begun, the material is standing still due to a straight portion on cam 82, the threading die is running on, the cut off tool is beginning its work and the turning tool swings slowly into the material.

Fig. 26 shows the position after completing the thread. The die is standing still and running off, the cut off tool has advanced deeper, the turning tool has completed its movement into the material and stands still.

The material together with the cut off tool begins to move forward on account of a steady rise on cam 82 pushing the guide 97 over the roller 98, the turning tool beginning to cut by reason of this movement of the material.

Fig. 27 shows the cutting off process advanced further and a part of the turning done. The slotting arm is moving into position for taking the next screw.

Fig. 28 shows the cutting off of the screw. The turning is completed because the feeding of the material and the simultaneous advance of the cutting off tool is stopped on account of the roller 85 riding on a circular part of the cam 82, slide 84 having reached the highest possible position.

Fig. 29 shows how the cutting off tool has advanced a trifle further to remove the tip remaining on the point of the screw, the turning tool has been swung back, the slotting arm has carried the completed part

away. The cutting off tool is now going to swing out of the material and to move back for the next piece, which movements are completed quickly by the auxiliary cam. shaft.

For comparing with the Figures 23 to 29, there is shown another set of diagrams Figs. 30 to 35, which shows the completion of the same screw in identical stages by another method, using a form tool for turning the body instead of the turning tool employed. Of course on parts of a more complicated shape both form and turning tools are used simultaneously because they are arranged entirely independent one of the other.

In order to use a form tool instead of a turning tool, it is necessary to adjust the guide 97 vertical and the guide 96 to an inclination corresponding to the total feeding movement required, completing in this manner the feeding operation during the period of the fast movement of the auxiliary cam shaft. No other changes are required, especially no new cams have to be inserted. The form tool may be placed either in the form or the turning tool carrier, preferably in the former, because it is mounted on the cut off tool carrier and any inaccuracy in adjusting the slide 97 vertically does not cause any trouble as only a slight feeding movement of the total combination can take place.

To produce a screw of a different diameter for instance larger as shown in Fig. 36, the radial movement of the cut off tool carrier must be increased by moving the roller 174 (Fig. 11) upwards. The spindle speed must be decreased by exchanging the gears 48, 49 (Fig. 9) and the ratio of the number of the spindle revolutions to one revolution of the cam shaft increased by changing the gears 51 and 52, in case the cutting speed and chip thickness is wanted to be kept uniform.

For extreme changes in diameter it may also become necessary to change the relative position of the two parts 61 and 61^a of the main cam shaft, because the fast speed of the auxiliary cam shaft remains constant, while the speed of the main cam shaft and of the slow movement of the auxiliary cam shaft changes at an inverse ratio with the square of the diameter of the material. Although the time consumed for the fast part of each revolution of the auxiliary cam shaft is very short—about one sixth of a second in the trial machine which has been built and operated—for parts of small diameter it may become important, as in this case the cam shaft completes each revolution in about one and one third of a second. This means that in such a case the main cam shaft turns 50° during the time used by the auxiliary cam shaft for the fast part of each revolution (205° in this extreme case). Some operations, for instance turning, should be tied up

to the beginning of the period of fast movement because the turning tool should just have been swung out of the way when the material advances. On the other hand, the

5 threading and forming operations should begin soon after the period of fast movement has been completed. The setting of the cam shaft parts 61 and 61^a is facilitated by a table based upon the change gears used.

10 To produce a screw with a different pitch of thread as for instance indicated in Fig. 37, it is necessary besides changing the die to set the angle of the guide piece 237 (Fig. 3) according to the lead and the ratio of 15 revolutions between main spindle and cam shaft.

To produce a screw of a different length, for instance shorter, as shown in Fig. 38, the guides 96 and 97 have to be adjusted 20 correspondingly and the slotting attachment has to be moved a trifle sideways.

To produce a screw Fig. 39 with a differently shaped head only cut off and turning tools of corresponding form need be employed.

A screw 40 with a turned down portion of the head requires a form tool for shaping this part and a turning tool for turning the body.

30 These examples show that it is possible to produce a great variety of screws and similar turned parts on a machine of this kind, without changing cams, during the time taken for the completion of the longest 35 operation, the cut off operation, plus the fraction of a second required for the unproductive operations.

In case another operation for instance the turning operation should take somewhat 40 longer than is possible with the feed ordinarily used for the cut off tool, this feed may be decreased a trifle by increasing the gear ratio between the main spindle and the cam shaft, producing in this case the part 45 with only a small increase of time.

Of course, if for any purpose it is desirable to exchange a cam, this may be done readily by using the known slip on construction with the hole in the cam slotted out to 50 the circular part of the curve, the part which has been cut out being fastened to the shoulder of the cam carrying sleeve.

If parts requiring principally a cut off 55 operation, like pins, rollers etc. with rather a great length in comparison to the diameter are to be made, it is to advantage to cut off right close to the collet. For this purpose the cut off tool carrier 155 is taken out of the arm 156, any axial movement of the bushing 164 is prevented by suitable collars on the tube 149 and the cut off tool is inserted 60 in the form tool holder 165.

Having now fully explained my invention I do not wish to be understood as limiting

myself to the exact details of construction 65 as obviously many modifications will occur to a person skilled in the art.

What I claim is:

1. In turning and screw cutting machines material feeding means reciprocating in an axial direction, rotatable material steadyng means without axial movement adapted to automatically grip the material when advanced by the feeding means, a drive shaft at one side of the axis of the feeding means 70 adapted to rotate said material steadyng means, cutting means connected to and moving axially of said shaft and means for swinging the cutting means to and from operative position.

2. In turning and screw cutting machines a material feeding mechanism including a gripping device for the material, means for moving said feeding mechanism to and fro in an axial direction, driving means for rotating said gripping device, cutting means connected to and moving axially with said feeding mechanism, and means for supporting the bar of material close to the cutting means adapted to be driven by said driving 90 means, said supporting means being held against axial movement and adapted to automatically grip the material when advanced by the feeding mechanism.

3. In turning and screw cutting machines 95 a reciprocating material feeding mechanism, material steadyng means held against axial movement and adapted to automatically grip the material when advanced by the feeding mechanism, cutting means connected to and moving axially with said feeding mechanism, means for moving said cutting means at right angles to the axial movement and driving means located between the feeding 100 mechanism and steadyng means adapted to simultaneously rotate the same.

4. In turning and screw cutting machines 105 a reciprocating material feeding mechanism rotating with the bar of material, means for supporting the material means for preventing axial movement of said supporting means, different means for causing said supporting means to automatically grip the bar of material subsequent to each advancing 115 stroke of the feeding mechanism, and cutting means connected to and moving axially with said feeding mechanism.

5. In turning and screw cutting machines 120 reciprocally mounted feeding means for moving a bar of material in one direction adapted to slide over the bar when moving in the opposite direction, cutting means moving with the feeding means, automatic gripping means for supporting the bar of material close to said cutting means adapted to operate following each advancing 125 stroke of the feeding means, means for moving said cutting means at right angles to the

5 bar of material and for bringing said cutting means to operate upon the bar of material in a radial direction, and additional cutting means adapted to operate upon the bar of material independently of the first mentioned cutting means.

10 6. In turning and screw cutting machines a bar feeding mechanism, cutting means moving with said feeding mechanism axially of the bar, automatic gripping means for supporting the bar of material close to said cutting means, a cam for moving said cutting means toward and into the bar, additional cutting means independent of the first 15 cutting means, and a cam for moving the second cutting means into the bar of material.

20 7. In turning and screw cutting machines a feeding mechanism, a cut off tool moving axially together with said feeding mechanism, means for moving said cut off tool radially independent of the axial movement, a turning tool held against axial movement, means for moving said turning tool radially 25 to operating position adapted to hold it a predetermined period for operating upon a bar of material controlled by said feeding mechanism, and automatic material gripping means held against axial movement 30 arranged relatively close to said cutting tools.

35 8. In turning and screw cutting machines reciprocating material feeding means, a plurality of separate cutting means moving axially together with said feeding means, separate means for moving said cutting means radially and independently of each other, additional cutting means movable independently of said first cutting means, and 40 automatic material gripping and supporting means held against axial movement and located close to said various cutting means.

45 9. In turning and screw cutting machines a reciprocating material feeding mechanism, material holding means, a support at one side of the axis of the feeding mechanism, cutting means pivotally and slidably mounted upon the support, means for reciprocating said feeding mechanism and said cutting 50 means, and cam mechanism for oscillating said cutting means.

55 10. In turning and screw cutting machines an automatic gripping mechanism for steady- ing a rod of material when cutting operations are being performed and for holding the rod against axial movement when the feeding mechanism moves back, a feeding mechanism moving back and forth for moving the rod of material through the machine, cutting means moving together with said feeding mechanism, and means for causing said cutting means to operate radially into the bar of material when moving forward and for holding said cutting means

away from the bar when moving in the opposite direction. 65

11. In turning and screw cutting machines a reciprocating material feeding mechanism, cutting means connected to and moving axially with said feeding mechanism, a cam for moving said cutting means radially at right angles to the reciprocating movement, a rocking member interposed between said cam and cutting means for changing the amount of the radial movement, and means for holding the radial movement constant irrespective of the reciprocal movement. 75

12. In a turning and screw cutting machine a rotating material spindle, material guiding means located upon and rotating with said spindle the latter being held against axial movement, a material feeding mechanism rotating also with said spindle and performing at the same time axial movements, and cutting means connected to and moving axially with said feeding mechanism, said guiding means being arranged relatively close to said cutting means. 80

13. In turning and screw cutting machines a feeding mechanism moving to and fro, rotatably mounted material supporting means held against axial movement, cutting means moving with said feeding mechanism and also arranged to swing on an axis at one side of and parallel to the axis of the feeding mechanism, a cam for operating the cutting means, and means for changing the throw of said cam. 85

14. In turning and screw cutting machines an automatic gripping mechanism, for holding a rod against movement in one direction, a feeding mechanism moving back and forth for advancing the rod through the gripping mechanism, cutting means moving with said feeding mechanism, separate cutting means, a cam for operating the first cutting means at right angles to the movement of the feeding mechanism and a member interposed between said cam and the first cutting means for changing the movement of said cutting means without changing cams. 100

15. In turning and screw cutting machines a slide, means for reciprocating said slide, a plurality of guides on said slide, said guides being linked together, and means for effecting simultaneous adjustment of said guides. 115

16. In turning and screw cutting machines a slide, means for moving said slide back and forth, a plurality of guides, the end of one guide being fastened to the end of the next guide, said guides being adjustable each independently of the other and means for clamping said guides upon the slide after adjustment has been made. 120

17. In turning and screw cutting machines a slide, means for moving said slide back and forth, a plurality of guides pivotally

- arranged on said slide to swing about a common axis whereby to vary the angular position of said guides in relation to the slide and means for clamping said guides to the slide after adjustment has been made. 5
18. In turning and screw cutting machines a slide, means for moving said slide to and fro, a plurality of guides arranged on said slide, the end of one guide being pivotally connected to the end of the next guide, indicating means for showing the angular position of said guides in respect to said slide means for simultaneously adjusting said guides and clamping means for fastening the guides to said slide. 10
19. In turning and screw cutting machines a slide, two cams, one for moving said slide in one direction and the other for moving the same in the opposite direction, two guides arranged adjustably on said slide, clamping means for fastening said guides to the slide, a reciprocally mounted feeding means and means controlled by said guides for actuating said feeding means. 20
20. In turning and screw cutting machines a slide, means for moving said slide to and fro, a plurality of guides arranged on said slide independently adjustable to different angles, means for clamping said guides to the slide, a member for transmitting movement from the guides at right angles to the slide and a reciprocally mounted work feeding device adapted to be actuated by said member. 30
21. In turning and screw cutting machines a slide, means for moving said slide back and forth, a plurality of guides arranged on said slide, independently adjustable to different angles, a feeding mechanism, a second slide operatively connected with said feeding mechanism and means movable upon the guides for transmitting the movement to said second slide. 40
22. In turning and screw cutting machines a slide, a plurality of guides arranged on said slide independently adjustable to different positions, a feeding mechanism movable at right angles to the slide reciprocally mounted means for actuating said feeding mechanism, and means for transmitting the movement from said guides to said reciprocally mounted means. 50
23. In turning and screw cutting machines a reciprocally mounted feeding mechanism, cutting means movable with said feeding mechanism, a member for moving said feeding mechanism and cutting means, two independently adjustable guides on a slide for actuating said member and means for moving the slide to and fro. 60
24. In turning and screw cutting machines, a material feeding mechanism, cutting means for performing turning operations in an axial direction, a drive shaft operatively connected with said feeding mechanism, different cutting means mounted upon said shaft for performing radial operations upon the bar of material, and adjusting means for varying the length of the turned portion irrespective of the length of the part produced. 70
25. In turning and screw cutting machines a material feeding mechanism, cutting means for performing turning operations axially on the bar of material, a drive shaft operatively connected with said feeding means, different cutting means pivotally mounted upon said shaft for performing radial operations, adjusting means for varying the length of material fed through the machine, and different adjusting means for varying the length of the turned portion irrespective of the length of the part. 75
26. In turning and screw cutting machines a material feeding mechanism, cutting means for performing turning operations axially on the bar of material, different cutting means for performing radial operations, means for controlling the movement of said feeding mechanism, whereby part of the feeding motion moves the bar of material past said turning means determining thus the length of the turned portion of the part produced, while the total feeding movement determines the length of the part, and adjusting means for varying the total feeding movement and the partial movement controlling the turning operation irrespective to each other. 80
27. In a turning and screw cutting machine a driving shaft rotating at a fast speed, a cam shaft making one revolution for each part completed on the machine and an auxiliary cam shaft also completing one revolution for each part produced, said auxiliary cam shaft being driven during part of one revolution by said driving shaft and the rest of the revolution by said cam shaft. 100
28. In turning and screw cutting machines a tubular spindle having tapered ends and having gear teeth between said tapered ends, a support open at its center to form an oil receiving space, spaced bearings carried by said support in which said tapered ends are journaled and oil grooves in said bearings and tapered ends adapted to permit oil to pass from and to return to said central space. 110
29. In turning and screw cutting machines a frame with two parallel bores, two bushings with conical bearings provided in each of said bores, two tubular parts with gear teeth cut on central portions of the same and with tapered ends fitting into said bushings, a driving shaft extending through one of said tubular parts and rotating the same, gripping means and a feeding mechanism, said gripping means and feeding mechanism being rotated by the other of the tubular parts. 120
- 150

30. In turning and screw cutting machines a main frame, a gear case fastened to said main frame, a thread mechanism bracket fastened to the opposite end of the main frame, two bushings located in a bore of this main frame each with a tubular part extending in the one case towards and into a bearing of the gear case, in the other case towards and into a bearing of the thread mechanism bracket, a gear supported in bearings of said two bushings for driving the material spindle, a gear for driving the threading spindle and a main shaft extending from the gear case through the tubular extensions of the said bushings into the thread mechanism and driving both gears. 70
31. In turning and screw cutting machines a gear for rotating the material spindle, two bushings providing bearings for said gear, each bushing with a tubular extension, a shaft passing through the tubular extensions of said two bushings and driving said gear and cutting means supported by and turning on said tubular extensions. 85
32. In turning and screw cutting machines gripping means for holding the rod of material, means for rotating said gripping means, a gear for driving said rotating means, two bushings supporting said gear each with a tubular extension and cut off means located turningly on said tubular extensions. 90
33. In turning and screw cutting machines a main spindle for controlling the movement of a bar of material, a threading spindle, means for rotating the threading spindle at a fixed relation to the speed of the main spindle, other means for advancing the threading spindle a fixed distance for each revolution made by it, the same means allowing the threading spindle to be pulled back at a certain time and different means for reversing instantaneously at the same moment the sense of the relative movement of the threading spindle in regard to the main spindle. 100
34. In turning and screw cutting machines a rotating shaft, a gripping mechanism for holding the bar of stock, means for turning said gripping mechanism at a fixed relation to said rotating shaft, a threading spindle, means for turning said threading spindle at a fixed but different relation to said rotating shaft, a cam for advancing the threading spindle, this cam turning at a fixed relation to said rotating shaft, means for pulling the threading spindle back and different means for reversing instantaneously the sense of the axial movement of said threading spindle. 110
35. In turning and screw cutting machines a main spindle, a threading spindle, means for rotating the threading spindle at a faster speed than the main spindle the relation of movement remaining fixed, other means for advancing the threading spindle a fixed dis- 115
- tance for each revolution made by it, the same means allowing said threading spindle to be pulled back at a fixed time and different means for interrupting instantaneously at the same moment the driving connection of said threading spindle making the same stand still. 120
36. In turning and screw cutting machines, a main spindle, a threading spindle rotating in fixed relation to but at a different speed than the said main spindle, a cam rotating in positive relation to said threading spindle, a slide being moved back and forth by said cam, guiding means fastened to said slide, adjustable according to the lead of the thread to be cut and the relation of speed of said cam and threading spindle and means for transmitting the movement from said guiding means to the threading spindle. 125
37. In turning and screw cutting machines a main spindle, a threading spindle, a coupling for rotating said threading spindle in fixed relation to but at a different speed than said main spindle, a cam rotating in positive relation to said threading spindle, a slide moving back and forth actuated by said cam, a plurality of adjustable guides fastened to said slide, means for transmitting the movement from said guides to the threading spindle and different means for interrupting instantaneously at a fixed position said coupling. 130
38. In turning and screw cutting machines a threading spindle, a cam rotating in positive relation to said spindle, a slide moving to and fro actuated by said cam, two guides located on said slide, said two guides being connected together at one end and arranged adjustable on said slide, and means for transmitting the movement caused by the guides to said threading spindle controlling the axial movement of the threading spindle. 135
39. In turning and screw cutting machines a main spindle, a threading spindle, a main shaft for driving rotatably both said threading spindle and main spindle, a gear driven by said main shaft, means for coupling said threading spindle to said gear, means for making and breaking this coupling connection and different means for controlling the axial movement of said threading spindle. 140
40. In turning and screw cutting machines a material spindle, a member rotating with constant speed, a coupling member engageable with said rotating member, a threading spindle turning with but moving axially independent of said coupling member, a stiff spring holding normally said coupling member out of engagement with said rotating member, a weak spring arranged to bring said coupling member into engagement with said rotating member when the influence of said stiff spring is removed, means for controlling the action of said stiff spring and a 145

- mechanism for controlling the axial movement of said threading spindle, said weak spring working together with said controlling mechanism to effect this result.
- 5 41. In turning and screw cutting machines a material spindle, a threading mechanism, a main shaft driving the spindle of said threading mechanism, a bracket for supporting said threading mechanism and for providing a bearing on which the threading mechanism may turn, this bearing being in line with said main shaft, a spring for holding said thread mechanism against a stop holding thus the spindle in line with the
- 10 15 material spindle, means for controlling the rotative motion of the threading spindle, and means for keeping said controlling means operative when rocking said thread mechanism bracket.
- 15 42. In turning and screw cutting machines a material spindle rotating the bar of material, a threading spindle located in a threading mechanism in line with the axis of said material spindle, a main shaft driving through gears both said material and threading spindles, a shaft rotating at a constant speed, change gears interposed between said main shaft and said shaft with constant speed, the latter one driving said
- 20 25 30 main shaft positively but at different ratios according to the change gears used, a slotting mechanism driven by said shaft rotating with constant speed and an arm for carrying the pieces after they have been cut off
- 35 40 45 50 55 from the bar of material and have been otherwise completed from the material spindle to the saw of said slotting mechanism.
43. In turning and screw cutting machines a drive shaft rotating at constant speed, a material spindle rotating in positive relation to said drive shaft, a pair of change gears interposed between said drive shaft and material spindle controlling the speed of said material spindle in relation to said drive shaft, a threading spindle rotating in fixed relation to said material spindle but with a different speed than the speed of said material spindle, a cam shaft rotating in positive relation to the material spindle and another pair of change gears interposed between said material spindle and cam shaft controlling the speed of said cam shaft in relation to said material spindle.
44. In turning and screw cutting machines a drive shaft rotating at constant speed, a slotting mechanism rotating in fixed and positive relation to said drive shaft, a material spindle rotating in positive relation to said drive shaft, change gears interposed between said drive shaft and material spindle controlling the speed of said material spindle in relation to said drive shaft, a threading spindle rotating in fixed and positive relation to but at a different speed
- than said material spindle, a cam shaft rotating in positive relation to said material spindle and other change gears interposed between said material spindle and cam shaft controlling the speed of said cam shaft in relation to said material spindle.
45. In turning and screw cutting machines a driving pulley, a drive shaft, a coupling for engaging said driving pulley with the drive shaft, a material spindle rotating in positive relation to said drive shaft, change gears interposed between said drive shaft and material spindle controlling the speed of said material spindle in relation to said drive shaft, a threading spindle rotating in fixed and positive relation to but at a different speed than said material spindle, a cam shaft rotating in positive relation to said material spindle and other change gears interposed between said material spindle and cam shaft controlling the speed of said cam shaft in relation to said material spindle,
46. In turning and screw cutting machines a cam shaft consisting of two parts adjustable against another, means for clamping these parts together after adjustment and an auxiliary cam shaft moving during each revolution faster and slower than the main cam shaft and completing each revolution in the same time as the main cam shaft.
47. In turning and screw cutting machines, a feeding mechanism, a cut off tool, a turning tool, a threading tool and means for having all said tools work simultaneously on a single bar of material.
48. In turning and screw cutting machines, a feeding mechanism, a cut off tool, a turning tool, a forming tool, a threading tool, and means for coordinating the movements of said tools and feeding mechanism to have all said tools work on a single bar of material simultaneously.
49. In turning and screw cutting machines with a single bar of material a feeding mechanism, a cut off tool, a turning tool, a threading tool, and means for coordinating the movements of said feeding mechanism and tools to have said turning tool and said threading tool complete their cutting operations during the time said cut off tool is working.
50. In one spindle turning and screw cutting machines a feeding mechanism, cutting means for working radially into the bar of material and for severing a part after it has been otherwise completed, different cutting means for working axially on the bar of material and producing turned portions, threading means, slotting means, and means for coordinating the movements of said feeding mechanism and said various cutting

means to have said turning means, said threading means, and said slotting means complete their cutting operations during the time said cutting means for severing the 5 parts are working.

51. In a machine of the class described, a frame, a hollow member rotatably mounted upon the frame, an automatic work gripping device carried on one end of said member and having a part guided therein, an automatic work gripping device at the other end of said member and having parts guided therein, the last mentioned device including reciprocally mounted means for feeding the 10 work axially through said member, operating means for moving said reciprocally mounted means axially of said member and means for rotating said member to effect rotation of one of said gripping devices.
52. In a machine of the class described, a frame, a hollow member rotatably mounted upon the frame, an automatic work gripping device carried on one end of said member and having a part guided therein, an 15 automatic work gripping device at the other end of said member and having parts guided therein, the last mentioned device including reciprocally mounted means for feeding the work axially through said member, operating means for moving said reciprocally mounted means axially of said member, 20 means for rotating said member to effect rotation of one of said gripping devices and

cutting means for the work adapted to be moved to a predetermined position by said 35 operating means.

53. In a machine of the class described, a frame, a hollow member rotatably mounted upon the frame, an automatic work gripping device carried on one end of said member and having a part guided therein, an automatic work gripping device at the other end of said member and having parts guided therein, the last mentioned device including reciprocally mounted means for feeding the 40 work axially through said member, operating means for moving said reciprocally mounted means axially of said member, and driving means for said member operatively 45 engaging the latter between its ends. 50

54. In a machine of the class described, a frame, a hollow member rotatably mounted upon the frame, an automatic work gripping device carried on one end of said member, an automatic work gripping device at 55 the other end of said member, the last mentioned device including reciprocally mounted means for feeding the work axially through said member, operating means for moving said reciprocally mounted means 60 axially of said member and means for rotating said member to effect rotation of said gripping devices.

In testimony whereof I hereunto affix my signature.

LORENZ KONRAD BRAREN.
